UNITED STATES PATENT OFFICE.

WALKER S. MILES, JR., OF MADERA, PENNSYLVANIA.

GAGE.

1,108,775.

Specification of Letters Patent.

Patented Aug. 25, 1914.

Application filed February 25, 1914. Serial No. 821,052.

To all whom it may concern:

Be it known that I, WALKER S. MILES, Jr., a citizen of the United States, residing at Madera, in the county of Clearfield and State of Pennsylvania, have invented new and useful Improvements in Gages, of which the following is a specification.

This invention relates to gages and in particular to a double-ended marking gage for use by carpenters or the like.

The primary object of the invention is to provide a gage of this character which includes a single bar of cylindrical construction upon which the slides are mounted, and which has marking elements provided at the ends thereof.

A further object is to provide radially adjustable marking elements at the ends of the bar which also are adapted to engage the slides to limit the outward movement thereof, the said slides being provided with longitudinal slots in communication with their cylindrical bores for the reception of the respective marking elements, when the former are turned into the proper angular relation thereto, to permit withdrawal of the slides.

A still further object is the provision of means for securing each slide normally against rotation upon the bar during its longitudinal adjustment thereon, the said means serving to secure the slide in adjusted position and being adapted normally to maintain the same in such angular relation to the bar that its slots will be out of alignment with the corresponding marking element.

The invention consists in the features of construction, combination, and arrangement of parts, hereinafter fully described and claimed, reference being had to the accompanying drawing, in which:

Figure 1 is a side elevation of the device; Fig. 2 is an end elevation of the same; Fig. 3 is a longitudinal sectional view taken through a portion of the same; and, Fig. 4 is a transverse sectional view taken on line 4-4 of Fig. 3.

In the drawing, the numeral 1 designates the cylindrical bar of the device upon which the slides 2 and 3 are rotatably and slidably mounted. A longitudinal groove 4 is provided in the bar 1 and each slide is provided with a set screw 5 having a knurled manipulating head 6, which is radially adjustable with respect to the bar and whose

inner end is adapted to project into the said groove for longitudinal sliding movement therein when partially loosened or for engagement with the bottom wall thereof when tightened to secure the slide in adjusted position upon the bar. A transversely elongated head 7 is formed upon the outer end of each slide to provide an outer guiding face 8 for coöperation with a radially disposed marking pin 9 which extends through an opening provided in the adjacent end of the bar 1 in communication with the groove 4. This marking pin fits tight within the receiving bar opening and is adapted, when first applied, to project outwardly in both directions, one end thereof being pointed for use in inscribing a line upon a timber or some other desirable object in parallel relation to one edge thereof, along which the guiding surface of the adjacent slide is moved. As the active extremity of the said pin becomes worn, the pin may be adjusted to allow for this wear by driving the pin through the bar opening to the desired extent. The bar 1 is graduated to provide a longitudinal scale of linear measurement extending inwardly from each marking pin, whereby the degree of adjustment of each slide may be determined. By loosening the set screw upon each slide to a slight extent, the latter may be adjusted longitudinally upon the bar and may be secured in adjusted position by tightening this screw.

It should be apparent that the slides are adapted to engage the respective marking pins, whereby they are limited against longitudinal movement in the direction of the bar ends and are thus prevented from becoming disengaged therefrom under normal conditions. It is desirable, however, that the slides should be capable of being removed and reapplied to the bar without the necessity of first detaching either of the marking pins. Each slide accordingly is provided with diametrically opposite, longitudinal slots 10 in communication with its medial bore, which may be brought into the same plane with the protruding extremities of the corresponding marking pin, when the said slide has been angularly adjusted upon the bar, after operation of the set screw to such an extent that its inner end is moved outward so as not to project into the bar groove 4.

From the foregoing description, taken in connection with the accompanying draw-

ings, it should be apparent that I have provided a simply constructed and efficient carpenter's gage comprising few parts, and which may be readily assembled or detached.

5. What I claim is:

1. A gage of the class described comprising a cylindrical bar having a longitudinal scale inscribed thereon, a slide mounted upon said bar for longitudinal movement and having an outer guiding surface, a radially disposed marking pin mounted in one end of the said bar with its active extremity projecting outward therefrom, the said slide being provided interiorly with a longitudinal slot opening through its opposite ends for the reception of the protruding end of the marking pin, the said slot being disposed normally in a plane at right angles to the said pin end, the bar being provided with a longitudinal groove in its outer periphery, and a radially adjustable set screw provided within the slide with its inner end engageable within the bar groove.
10. means by which the slide may be secured in adjusted position upon the bar, and means cooperating with the said securing means for preventing rotation of the slide upon the bar during its longitudinal movement thereon, the said slide being provided interiorly with a longitudinal slot opening through its opposite ends for the reception of the marking pin, the said slot being disposed normally in a plane at right angles to the pin.
15. 20.

2. A gage of the class described comprising a cylindrical bar having a longitudinal scale inscribed thereon, a slide mounted upon said bar for longitudinal movement and having an outer guiding surface, a radially disposed marking pin mounted in one end of the said bar with its active extremity projecting outward therefrom, the said slide being provided interiorly with a longitudinal slot opening through its opposite ends for the reception of the protruding end of the marking pin, the said slot being disposed normally in a plane at right angles to the said pin end, the bar being provided with a longitudinal groove in its outer periphery, and a radially adjustable set screw provided within the slide with its inner end engageable within the bar groove.
25. 30.
35. 40.

In testimony whereof I affix my signature in presence of two witnesses.

WALKER S. MILES, JR.
